UNITED STATES PATENT OFFICE

CARLYLE N. MONTANYE, OF BALTIMORE, MARYLAND

DESIGN FOR A CALENDAR EASEL

Application filed October 6, 1931. Serial No. 41,310. Term of patent 3½ years.

To all whom it may concern:

Be it known that I, CARLYLE N. MONTANYE, a citizen of the United States of America, residing at the city of Baltimore, State of Maryland, have invented a new, original, and ornamental Design for Calendar Easels, of which the following is a specification, reference being had to the accompanying drawings, forming part thereof.

Fig. 1 is a front elevation of a calendar easel, showing my new design.

Fig. 2 is a plan view of a calendar easel, showing my new design.

I claim:

The ornamental design for a calendar easel, as shown.

CARLYLE N. MONTANYE.
